US00D921691S

(12) **United States Design Patent** (10) Patent No.: **US D921,691 S**
 Park et al. (45) Date of Patent: ** Jun. 8, 2021

(54) **DISPLAY SCREEN WITH GRAPHICAL USER INTERFACE**

(71) Applicant: **LG Electronics Inc.**, Seoul (KR)

(72) Inventors: **Jungin Park**, Seoul (KR); **Sukhyun Lim**, Seoul (KR); **Saekyu Park**, Seoul (KR)

(73) Assignee: **LG ELECTRONICS INC.**, Seoul (KR)

(**) Term: **15 Years**

(21) Appl. No.: **35/508,130**

(22) Filed: **Jun. 11, 2019**

(80) **Hague Agreement Data**

Int. Filing Date: **Jun. 11, 2019**
 Int. Reg. No.: **DM/203676**
 Int. Reg. Date: **Jun. 11, 2019**
 Int. Reg. Pub. Date: **Dec. 13, 2019**

(30) **Foreign Application Priority Data**

Dec. 11, 2018 (KR) 30-2018-0058312
 (51) LOC (13) Cl. 14-04
 (52) U.S. Cl. USPC **D14/486**; D14/488
 (58) **Field of Classification Search** USPC D14/485-495
 CPC ... G11B 19/025; G06F 3/0484; G05B 19/418;
 G01C 21/36; G08G 1/096; G08F 1/123;
 B60K 37/00
